UNITED STATES PATENT OFFICE.

GEORGE WILBUR GWINN, OF NEW YORK, N. Y., AND JAMES W. LEARY, OF ALLENDALE, NEW JERSEY, ASSIGNEES TO AUTOMATIC PACKING & LABELING COMPANY, OF DURHAM, NORTH CAROLINA, A CORPORATION OF NORTH CAROLINA.

MACHINE FOR APPLYING STAMPS AND THE LIKE TO PACKAGES OR CONTAINERS.

1,425,250.

Specification of Letters Patent. Patented Aug. 8, 1922.

Application filed October 10, 1917. Serial No. 195,769.

To all whom it may concern:

Be it known that we, GEORGE W. GWINN, a citizen of the United States, and resident of New York, in the county of New York and State of New York, and JAMES W. LEARY, a citizen of the United States, and resident of Allendale, in the county of Bergen and State of New Jersey, have invented certain new and useful Improvements in 10 Machines for Applying Stamps and the like to Packages or Containers, of which the following is a specification.

This invention pertains to an improved machine for applying stamps or the like to packages, and more specifically to an improved means for applying revenue stamps to packages or containers filled with tobacco.

The main object of the invention is to provide means for expeditiously and with certainty placing stamps upon packages. Working in conjunction with said placing means are devices which present the packages to stamp placing means and thereafter clamp or press the central portion of the 25 stamp against the package after which the stamp ends are wiped down, the stamps at the corners or edges of the packages thereafter being pinched or rolled closely to the package and finally the stamp ends are 30 dried.

A still further object is to provide a special form of stamp presenting and placing mechanism, wherein the stamps are pasted along one face and laid or stretched 35 out on a supporting frame or table, which table is then so moved as to bring the stamp into line with the oncoming package which contacting with the stamp draws it from the table and then moves into cooperative 40 position with means for carrying the stamp ends into contact with the body of the package.

With these and other objects in view which will appear in the following description and having in mind that the term "stamp" is employed to include bands, labels, sealing strips and the like, reference is made to the drawings, wherein:

Fig. 1 is a longitudinal vertical sectional view, taken centrally of the machine;

Fig. 2 a transverse sectional view on the line II—II of Fig. 1, looking toward the stamp holder;

Fig. 3 is a horizontal sectional view on the line III—III of Fig. 2; 55

Fig. 4 is a sectional elevation illustrating a portion of the driving mechanism and the stamp transferring support or table;

Fig. 5 is a sectional elevation of the same 60 parts, the line of section being V—V of Fig. 4;

Fig. 6 is a detail view of the stamp feeding mechanism the stamp being in a less advanced position from that illustrated in 65 Fig. 5;

Fig. 7 a horizontal sectional view of the stamp-transferring support or table showing a stamp being withdrawn therefrom by a forwardly moving package; 70

Fig. 8 a detail sectional view of one of the package clamps or carriers;

Fig. 9 a plan view of the driving shafts and allied parts;

Fig. 10 a detail view of the gearing employed to drive the stamp withdrawing rolls and the driving shafts for the combined paste applying and stamp extending or positioning belts; 75

Fig. 11 a detail view of the stamp guide 80 and stripper and allied parts;

Fig. 12 a detail sectional view, on an enlarged scale, taken on the line XII—XII of Fig. 1; and Figure 13 a detailed view of 85 a modified form of the stamp transferring support or table.

In the drawings 1 denotes the bed or table which forms the support for the various mechanisms. The main driving shaft 2 is supported in suitable hangers or 90 brackets extending downwardly from the table and is provided with fast and loose pulleys 3 and 4, Fig. 9.

A counter shaft 5 is arranged parallel to shaft 2 and an intermittent motion is imparted to shaft 5 through the actuating arm 6 which forms a part of a Geneva movement the stop member whereof is denoted by 7, and the actuated member by 8, the latter being pinned or otherwise made 100 fast to shaft 5. Shaft 2 also has secured to it a second actuator 9 and stop 10, which cooperate with a second actuated member 11 which is loose upon shaft 5. The first Geneva movement, as noted, imparts a step-by-step movement to shaft 5 which motion in turn is transmitted to the stamp trans-

fer table or mechanism, while the second Geneva movement transmits a step-by-step motion to the package carrier or package advancing means.

5 Said package advancing means in the form illustrated may be said to comprise an endless chain or carrier provided with a series of package clamps or holders.

Located at either end of the table are 10 shafts 12 and 13, Fig. 1, a pair of laterally spaced sprocket or pocket wheels 14—14 and 15—15, respectively, being mounted thereon.

Wheels 15—15 are made fast to shaft 13 15 which likewise carries a sprocket about which passes a sprocket chain 16, the lower bight of which passes about a sprocket secured or formed upon the hub 17 of the Geneva movement element 11, see Fig. 9, 20 which as before noted is loose upon shaft 5, being held in place by collars 18—19 pinned to shaft 5.

The endless package carrier in the form illustrated comprises a series of interconnected holders each having a fixed jaw and a movable clamping jaw with an intermediate package support. As will be seen upon reference to Figs. 1, 2, 3, 7 and 8 the support 20 and the fixed jaw 21 are formed 30 integrally, the inner face of the jaw being slightly beveled and entering the countersunk adjacent end of the package designated by 22.

Extending downwardly from the support 20 are two arms 23, each having a hub 24, Figs. 3, 7 and 8. A pin 25 extends through said hubs and likewise through rollers 26. A second pair of arms 27 extend from the support 20 at the advancing 40 end thereof and a clamping jaw having the shape of an elbow lever, the upper end 28 whereof forms the clamping jaw proper is fulcrumed upon a pin 29 mounted in the lower ends of said arms 27. The lower or 45 inner end 30 of the lever carries a roller 31 which coacts with cams 32 and 33, Fig. 1, as will be presently explained.

Clamping jaw 28 is urged toward the fixed jaw by a spring 34, see Fig. 8.

50 The various carriers are connected to each other by links 35, said links being connected in parallel pairs to pins 25 and 29, said pin 29 likewise carrying rollers 36 similar to rolls 26.

55 Suitable tracks 37, see more particularly Fig. 2, are mounted on the upper face of the bed, in line with the rollers 26—26 and support the upper run of the carrier. Similar tracks 38 are secured to brackets 39 projecting downwardly from the under side of the table and extend the length thereof. Said tracks co-operate with rails 40 also secured to brackets 39 to hold and guide the lower run of the carrier and cause the rollers 31

to successively contact with cam 33 to open the clamping jaw 28 and discharge the stamped package as shown in Fig. 1. A third cam 41, Figs. 1 and 12, is arranged at the intake end of the machine and acts to successively open the fixed jaws for 70 the introduction of the packages into the carriers, which may be effected by the mechanism shown in said figures, as will be hereinafter described, or by hand, as desired.

Guide rails 42, Figs. 1 and 3, spaced apart a 75 distance equal to the thickness of the package or slightly in excess thereof, extend from the point of intake to the point where the stamp is being applied at which time the clamping jaw is opened by the cam 32. 80

The stamp feeding mechanism in so far as the withdrawal of the stamps from the magazine and the application of paste thereto are concerned, is substantially the same as that shown and claimed in the application 85 of George W. Gwinn, filed on or about the 20th day of May, 1914, Serial No. 839,835, in which case the stamp was fed directly onto the package. In the present instance the pasted stamp is fed out onto a support 90 or table which is then rotated to carry the stamp into line with the package, the package as it is moved contacting with the central exposed portion of the stamp and withdrawing it from the support. A plurality 95 of such supports are preferably provided so that the machine may be given a high speed.

Secured to and extending upwardly from the table are two vertical columns 43—43 100 to the upper ends of which is secured a cross frame 44 having vertical slide ways formed therein for the reception of a plate 45. To the forward face of the plate is secured the stamp magazine 46 the forward 105 face whereof is preferably open while the bottom is cut away or formed with an opening to expose the central portion of the lowermost stamp to the withdrawing rolls. The magazine is shown in Fig. 2 as partly 110 filled with stamps designated by 47 and a follower weight 48 is preferably placed on top of the pile to hold the stamps in place and in coactive relation with the two withdrawing rolls 49. Said rolls are constantly rotated through gearing presently 115 described and it is therefore necessary to raise and lower the magazine toward and from the same to effect the complete withdrawal of one stamp before another is acted 120 on by the rolls. To this end the following devices are employed.

Mounted in suitable hangers 50, Fig. 1, is a shaft 51 to which is secured a bevel gear 52 which meshes with a gear 53. See 125 Fig. 9. Said shaft has secured to it a cam 54, and a roller 55 carried by a lever 56 journaled at its opposite end on a fixed shaft 57 works in the groove of said cam. Fulcrumed upon the upper end of an upwardly 130

extending post 58 is a lever 59 said lever being connected to lever 56 by a connecting rod 60. The free end of lever 59 projects outwardly in rear of the upwardly extending portion of frame 44 and a pin 61 extending therefrom passes through an opening in frame 44 and into a slot formed in the lower end of slide 45.

Cam 54 is so formed as to lift the magazine after the lowermost stamp has been partially withdrawn by rolls 49 and to maintain it in such position until the parts are again ready to receive another stamp.

The stamps are adapted to be withdrawn one by one and pasted along one face thereof, the stamps being spread out with the pasted face in contact with supporting and transfer plates which are open at the center so that the oncoming package may contact with the stamp thus supported and withdraw the same from the plates.

Extending upwardly from the table, (see Figs. 1 and 11) is a column 62 to which there is pivoted upon a stud or bolt 63, a lever 64 and also a bell-crank 65. Lever 64 is raised and lowered through a rod 66 the lower end of which (see Fig. 2) is connected to a lever 67 fulcrumed on shaft 57. Lever 67 carries a roll 68 which works in the groove of a cam 69 secured upon shaft 51. Lever 64 carries at its outer end a combined guide and label stripper comprising an arm 70 which at its lower end is broadened out and extended laterally and to which lateral extension are secured two fingers 71 and 72. Said fingers are thin, are separated at their upper ends, and converge toward the central portion, the lower ends standing a slight distance apart in parallel relation (see Figs. 1, 2 and 11). A link 70' pivotally connected to the upper end of bell-crank 65 and to the upper end of arm 70 tends to maintain the guide and stripper in its vertical position as it is raised and lowered by lever 64. The paste is applied to the stamp by belts, four in number, and arranged in pairs. One pair is designated by 73-74 and the other by 75 and 76.

Belts 73-74 pass about a pulley 77, Figs. 2 and 3, having two grooves formed therein for their reception and likewise at the opposite bight thereof about a pair of grooved pulleys or wheels 78 and 79.

Belts 75 and 76 pass about similar pulleys and wheels bearing similar numerals with the exponent α imposed thereon.

Wheels 78 and 79, and 78 α and 79 α are so spaced as to permit the stripper and guide fingers 71-72 to pass down between them and between the adjacent portions of the belts and to strip the stamp from the belts in the manner hereinafter set forth.

Pulley 77 is mounted on a shaft 80 and pulley 77 α on a shaft 81, and each of said

shafts, see Fig. 3, has secured to it a bevel gear 82 and 83, respectively, which mesh with similar gears 84 secured upon a shaft 85. Shaft 85 has secured to it a pinion 86 which meshes with a pinion 87, Fig. 2, 70 which latter derives its motion through a sprocket wheel 88, mounted on its hub and driven by a chain 89. The sprocket chain in turn is driven from a sprocket 90, Figs. 1, 2 and 9, secured upon shaft 2.

Each of the shafts 80 and 81, carries a pinion 91 and meshes with a gear 92 secured upon a shaft 93 which shaft also carries two paste transfer rolls 94-95, Fig. 3. The peripheries are slightly roughened or milled and lightly contact with the overlying paste applying belts 73-74 and 75-76. Said rolls 94-95 dip into the paste or other suitable adhesive contained in the reservoirs or boxes 96.

The wheels 78, 79 and 78 α and 79 α are fast to shafts 97 and 98 respectively, said shafts finding their bearing in adjustable brackets 99 secured to a fixed cross bar 100, see Fig. 10. Said shafts 97 and 98 carry 90 intermeshing driving gears 101 and 102, and the latter is in mesh with a gear 103. The shaft 104 upon which gear 103 is secured likewise carries a worm wheel 105 which meshes with a worm 106 secured upon shaft 95 85. The stamp withdrawing rollers 49, see Figs. 1 and 10 are secured upon shafts 107 and 108 the latter carrying a gear 109 which meshes with gear 103 and receives motion therefrom. Shaft 108 also carries a smaller 100 gear 110 which meshes with a similar gear 111 secured to shaft 107.

From the foregoing it will be seen that all of the belt supporting rolls and pulleys and the stamp withdrawing rolls are operated 105 from the common driving shaft 85. The stamps as above noted are drawn one at a time from the stamp-magazine by the constantly rotating withdrawing rolls 49, the central portion of the lowermost stamp being caught between said rollers, doubled upon itself and carried downwardly between the rolls and directed between the paste applying belts by the combined guide and stripper. As the stamp is withdrawn 110 from the magazine, the latter is raised to carry the next succeeding stamp free of the rolls and as the bend in the stamp passes between and beyond the paste applying belts the stripper is raised, see Figs. 6 and 5.

The folded stamp as it passes down between the belts has paste applied in lines on the under or outermost face thereof and to provide means for arresting and transferring the stamp into line with the package 125 carrier, the following mechanism is employed.

Extending upwardly from the bed 1 upon opposite sides of the track 37 are posts or columns 112 and 112 α . In each of these col- 130

umns is journaled a shaft designated by 113 and 113^a respectively, each shaft carrying a sprocket wheel 114, 114^a, at its outer end and deriving its motion through sprocket 5 chains 115, 115^a, and sprockets 116 and 116^a secured upon the counter shaft 5, which shaft, as will be recalled, has a step by step rotation imparted to it.

To the inner adjacent ends of each of the 10 shafts 113, 113^a is secured a spider frame having in the form shown four radiating arms designated by 117, and to the other end of each arm is secured a flat plate 118. The outer face of said plates are given a 15 smooth or burnished finish, and the proximate ends of each pair are separated a distance somewhat greater than the width of the package carrier and the package to which the stamps are applied. Each pair 20 of plates may be said to comprise a transfer table or support upon which the pasted stamp is rolled out, and by which it is carried into line with the package end to which it is to be applied.

25 Inasmuch as the stamp is carried downwardly in a folded or doubled condition by the paste belts in line with the opening between the plates, means is provided for arresting the stamp, said means taking the 30 form of a narrow blade 119. Said blade is secured upon the outer end of an arm 120 fixed to a rocker shaft 121 which finds its bearings in the columns 43. A second arm or lever 122 is secured to said shaft, the free 35 end of the lever, see Figs. 2 and 4, overlying one of a series of equally spaced cams, 123 carried by the hub of sprocket 114. The parts are so timed that the upper edge of plate 119 is carried up into alignment with 40 the then uppermost plates 118 so that the downwardly moving stamp, see Figs. 2, 5 and 6, contacts therewith, is arrested thereby, and is carried outwardly by the paste applying belts and laid upon the plates or two-part 45 table. When this is effected, shafts 113 and 113^a are given a quarter turn and at the beginning of such movement the then uppermost cam 123 rides from beneath lever 122 and permits blade 119 to drop away from the 50 central portion of the stamp. By reason of the fact that only a narrow edge or surface of said blade is in contact with the stamp, and the further fact that it contacts with the stamp between the lines of paste applied to 55 the stamp, there is no tendency for the blade to stick to the stamp and to draw the same inwardly or downwardly between the plates 118 upon which the stamp is laid out.

Upon the completion of the quarter revolution of the stamp carrier the pasted stamp 60 comes to rest in the position shown in Figs. 1, 2 and 3, standing forward of the package and in rear of the package clamping lever or member 28 which is at such time thrown 65 open by the fixed cam 32. The package car-

rier is of course at rest at such time so that the pasted stamp may be carried into position with the package without disturbing the stamp. When the stamp comes to rest in front of the package the conveyor again begins its movement and the roller 31 rides off cam 32 and allows the spring 34 to draw the clamping jaw into contact with the central portion of the stamp and to press the same firmly against the package end. As the conveyor and the clamped package move forward, see Fig. 7, the stamp is drawn off the plates 118 and carried and pressed into contact with the sides of the package by a pair of oppositely-disposed pressure members, as 70 fixed brushes 124. The carrier, by reason of the step-by-step motion which is imparted thereto, comes to rest with the package between the brushes 124 and the stamp ends dry more or less while thus held. A succeeding pair of brushes 125 receive the package as it is advanced another step and hold the stamp ends; said brushes may be somewhat stiffer than the others.

From brushes 125 the packages are passed 75 between two series of rollers 126, which rollers act to crease or pinch any protruding portion of the stamp which may be left at the edge of the package inwardly toward the clamping jaw 28, so that no portion of the 80 stamp will be left projecting upward beyond the edge of the package. In other words if there be any slack in the stamp which tends to form a projection at each edge of the package such projections when they contact 85 the rolls as the package is advanced forwardly therebetween will be turned inwardly toward the package. It is desirable in the handling of such packages or the packing of such packages into cartons or containers that 90 there be no projections as the stamps or labels are apt to be torn and such projections interfere with the proper handling and storing of the goods. After leaving the rollers, 95 the packages will preferably pass between 100 oppositely-disposed heaters 127 (preferably 105 electric).

As above indicated, the packages may be fed into the machine either automatically 110 or by hand, and in Figs. 1, 2 and 12 there is shown a mechanism whereby the packages 115 may be automatically delivered to the package-advancing or holding means. A feed belt 128 is located at one side of the bed and travels over pulleys 129 and 130. Said belt 120 is designed to deliver the packages sidewise onto an inclined plate or bed 131 supported by a bracket 132, mounted on the bed or table 1. Curved guide bars 133 overlie the upper end of the plate 131 and the belt adjacent the pulley 130, said bars being supported by suitable arms 134 secured to the guide rail 42. The packages, as they pass 125 down the plate 131, come to rest upon two horizontally-disposed supporting bars or 130

rails 135, the ends of the rails adjacent the plate being slightly curved. The rails at their opposite ends terminate adjacent the supporting element 20 of the carrier, so that the packages may be transferred from the plate 131 along the rails 135 and onto the carrier. The plate 131 is provided with an opening through which the plunger 136 may be projected to transfer the overlying package laterally into the package-holder or carrier between the jaws 21 and 28. The jaw 28 is at such time in its retracted position by reason of the roller 31 coming in contact with cam 41, as best shown in Fig. 15. 1. The plunger 136 is provided with a rearwardly-projecting guard plate 137 which is carried forwardly with the plunger and serves to hold the next succeeding package from dropping downwardly while the lowermost package is being carried forwardly into the package-carrier.

The plunger 136 is carried by an arm 138, fulcrumed upon a shaft 139, mounted in a bracket 140 extending downwardly from the bed or table 1. Shaft 139 also has secured to it a second arm or lever 141, and a link 142 pivotally connected to the lower end of said arm is attached to a crank 143, secured to the shaft 51. From this it will be seen that the plunger 136 acts in timed relation with the other portions of the machine to introduce a package into the open holder while the same is at rest and in line therewith.

From the foregoing description it is thought that the operation of the machine will be clearly understood, and while the structure has been set forth somewhat in detail it is to be understood that it may be modified so long as it falls within the scope of our invention. Thus, for instance, any stamp feeding and pasting mechanism which will apply the paste and impose the stamps upon the rotating table may be employed in lieu of that set forth. So, too, any form of carrier which will advance the packages into contact with the pasted stamp and cause the same to strip the stamp from the table or support may likewise be employed though the present form is preferred.

Plates 118 may take a form other than that shown such, for instance, as two drum shaped members having flattened sides as shown in Fig. 13.

It is also conceivable that instead of employing a plurality of pairs of plates, a single pair may be employed but the form shown is preferred as the use of a single pair would materially slow down the operation of the machine as will be readily appreciated.

Again, while the jaws 21 and 28 of the carrier are both shown of a form to co-operate with a package having oppositely disposed, indented ends, it is conceivable that one end only of the package may be

indented, or that to which the stamp is applied, in which case the jaw 21 may be shaped to conform to the flat or otherwise formed end of the package. In fact, packages neither end of which is indented may be stamped with the machine, and the jaws of the clamping members modified or not as may be found necessary or desirable.

The use of the term "package" is not intended to confine the use of the structure to the particular package shown, but is employed in a broad sense and in the claims is intended to cover tins, boxes, etc., except in those instances where, by reason of the structure included, a special form of package alone could be employed.

Having thus described our invention, what we claim is:—

1. In a machine for applying stamps, the combination of a table; means for applying paste to a stamp and simultaneously laying the same in adhesive relation with the table and with a portion of such pasted face exposed; package holding means; and means for securing a relative movement between the table and holding means and causing the exposed portion of the stamp and package to contact whereby the stamp will be stripped from the table.

2. In a machine for applying stamps, the combination of means for receiving the pasted side of a stamp and holding the same in an extended position by reason of adhesive relation between the stamp and said receiving means; means for simultaneously applying paste to one side of the stamp and spreading it out upon said receiving means; and means for moving the package into contact with the stamp and stripping the stamp from said receiving and holding means.

3. In a machine for applying stamps, the combination of stamp receiving means; means for applying adhesive to a stamp throughout its length and simultaneously placing the pasted side upon said receiving means with a portion of the stamp between its ends exposed; and means for advancing a package against said exposed portion and through a continued movement thereof, stripping the stamp from said holding means.

4. In a machine for applying stamps, the combination of stamp supporting means; means for simultaneously applying paste to the stamp and placing such pasted stamp upon said supporting means, the stamp being held thereon by adhesion of the paste, with a portion of the pasted face of the stamp exposed; and means for advancing a package against such exposed portion, and through a continued movement of the package, pulling the stamp from its supporting means.

5. In a machine for applying stamps, the combination of stamp receiving means;

means for pasting a stamp and simultaneously placing the pasted face thereof in contact with the receiving means; and means for transferring said receiving means with the stamp thereon into the path of movement of the package sustained by the package advancing means, whereby the package will contact the pasted stamp and through a continued movement strip the stamp from said receiving means.

6. In a machine for applying stamps, stamp receiving means; means for applying paste to the stamp and simultaneously laying the same out upon said receiving means with the pasted face in contact with said receiving means, and with a portion of said pasted face exposed; and means for moving the stamp receiving means into the path of movement of the package carried by the advancing means.

7. In a stamp applying machine, the combination of means to receive and hold the stamp by reason of the adhesion of the latter thereto, with a portion of the pasted side of the stamp exposed; stamp feeding and pasting means adapted to simultaneously apply paste to the stamp and lay the same directly upon the receiving means, said parts being located in juxtaposition; and means for carrying a package into contact with the exposed pasted portion of the stamp.

8. In a machine for applying stamps, a supporting surface for the stamp; means for applying paste to one face of a stamp and laying the stamp in an extended form and in adhesive contact with the supporting surface with a portion of the pasted stamp exposed; means for presenting a package to said exposed pasted portion; and means for securing a relative movement between the stamp and package whereby the stamp will be withdrawn from the support and into contact with the package.

45 9. In a machine for applying stamps, the combination of a supporting surface adapted to receive and hold a stamp; means for simultaneously applying paste to one face of a stamp and laying the pasted stamp in an extended form with its ends in adhesive contact with such supporting surface and with the center thereof exposed; means for aligning a package with said exposed section; and means for securing a relative movement 55 of the package and the stamp, whereby the stamp will be withdrawn from the support and into contact with the package.

10. In a machine for applying stamps, the combination of a pair of stamp supporting elements separated at their proximate ends; means for simultaneously applying paste to one face of the stamp throughout its length, and depositing the same upon the supporting elements in adhesive contact therewith.

11. In a machine for applying stamps, the combination of a pair of stamp supporting elements separated at their proximate ends and each having a smooth or planished face; and means for applying paste to a stamp and simultaneously placing the ends thereof upon said supporting elements in adhesive contact with the planished faces thereof. 70

12. In a machine for applying stamps, the combination of a pair of supporting elements separated at their proximate ends and each having a smooth or planished face; means for applying paste to the stamp and simultaneously laying the same with the pasted side thereof into adhesive contact with the planished faces; and means for advancing a package between the proximate ends aforesaid into contact with the stamp and by a continued movement of the package withdraw the stamp from the supporting 85 elements.

13. In a machine for applying stamps, the combination of a pair of supporting elements separated at their proximate ends and each having a smooth or planished face; 90 means for applying paste to one face of the stamp throughout its length and simultaneously placing the same in adhesive relation with the planished faces; means for advancing a package between the proximate ends aforesaid into contact with the stamp, and by a continued movement of the package withdraw the stamp from the supporting elements; and means acting on the stamp ends to press them into contact with the 95 package.

14. In a machine for applying stamps, the combination of a pair of supporting elements separated at their proximate ends; means for applying paste to the stamp throughout its length and simultaneously placing the ends thereof into adhesive relation upon said supporting elements; package advancing means; and means for moving the supporting elements with the stamp thereon into alinement with the oncoming face or end of a package presented by said package advancing means. 110

15. In a machine for applying stamps, the combination of means for applying paste to the stamp; a pair of stamp receiving and supporting elements separated at their proximate ends; a device located intermediate said ends; stamp pasting and positioning means adapted to fold a stamp and to contact the fold thereof with said intermediate device and to then carry the ends of the stamp outwardly and lay the pasted face thereof in contact with the supporting elements; and means acting to remove the intermediate device from contact with the central portion of the pasted stamp. 115

16. In a machine for applying stamps, the combination of a pair of stamp receiving elements separated at their proximate ends; 120

means bridging the space between said ends; means for placing a pasted stamp upon said receiving elements and over the bridging means; package presenting means; and 5 means for removing said bridging means out of contact with the stamp and moving the supporting elements such distance as to bring the stamp carried thereby into line with the package advanced by said presenting means, whereby upon continued advancing movement of the package the stamp will be withdrawn thereby from the receiving elements.

17. In a machine for applying stamps, the 15 combination of a stamp magazine; a stamp receiving and transferring mechanism located beneath the same; means for imparting a step-by-step rotation thereto; stamp withdrawing and pasting means arranged 20 to withdraw the stamps, one by one, and place the same in adhesive contact with the receiving transferring mechanism; a package presenting mechanism; and means, working in timed relation to the stamp presenting mechanism, to cause an advance movement of the package advancing mechanism.

18. In a machine for applying stamps, the 30 combination of a stamp magazine; a structure presenting a plurality of stamp receiving surfaces, said surfaces having an open space therein; means for imparting a step-by-step rotative movement to said structure; means for withdrawing stamps one by one from the magazine; means for applying 35 paste to one face of the stamps and spreading them out at the receiving surfaces with the stamp bridging the space aforesaid; and means for successively advancing packages through said stamp receiving structure and into contact with the exposed pasted portion of the stamps as they are brought into the path of movement of the packages.

19. In a machine for applying stamps, the 45 combination of a stamp magazine; two spider frames located below the same with horizontally disposed aligning supporting shafts; a plurality of plates secured to each frame, the plates of one frame aligning with those of the other in pairs, with the proximate ends of each pair separated; means for imparting a step by step rotation to said frames; a bridge piece; means for raising said bridge piece into the space 50 between the ends of the then uppermost pair of plates; means for withdrawing a stamp from the magazine and folding the same back upon itself as withdrawn; paste applying mechanism adapted to grasp the 55 stamp, to project the folded portion thereof against the bridge piece, and to carry the ends laterally onto the plates; a package holder; and means for advancing the holder and the package therein through the intervening space between the stamp support-

ing plates when said plates with the stamp thereon are moved into alignment with said carrier.

20. In a machine for applying stamps, the combination of a support adapted to receive the pasted side of a stamp, said support having a space or opening therein; means for applying paste throughout the length of one face of the stamp and simultaneously placing the pasted side thereof in 70 contact with the support; and means for passing a package through said opening and into contact with the pasted face of the stamp.

21. In a machine for applying stamps, the 80 combination of means for applying paste to a stamp; a support adapted to receive the pasted side of the stamp and to temporarily hold the same with a portion of said pasted side exposed; a carrier comprising a series 85 of package holders, each holder having a movable clamping jaw adapted to contact with the package; means to temporarily open said jaw; and means for moving the stamp support to carry the exposed portion of the 90 stamp between the jaw and the adjacent end of the package.

22. In a machine for stamping packages the combination of means for applying paste to a stamp; a support adapted to receive and 95 temporarily hold such stamp by the adhesion of the pasted face of the stamp and leaving a portion of such pasted face exposed; a carrier comprising a series of package 100 holders each having a movable clamping jaw adapted to contact with the package; means for moving the stamp support to carry the exposed portion of the stamp between the jaw and the package; means for advancing the carrier and causing the jaw to clamp 105 the stamp and upon further movement to draw the stamp from its support; and means for pressing the ends of the stamp against the package.

23. In a machine for stamping packages, 110 the combination of means for pasting one face of a stamp and simultaneously imposing the ends of such pasted face upon a support with the central pasted portion exposed; a package carrier; means for advancing the same and causing the package 115 to contact with the exposed pasted surface of the stamp and thereby stripping the stamp from its support; and means for pressing the ends of the stamp against the package. 120

24. In a machine for applying stamps to packages, the combination of an endless carrier having a series of package holders, each holder comprising a supporting member, a fixed jaw, a movable jaw, and a spring for 125 drawing said movable jaw toward the fixed jaw; means for advancing said carrier step by step; means for temporarily opening the movable jaws when they reach a predetermined point in their path of travel; means 130

for placing and holding a pasted stamp between said open jaw and the package in the holder; means for advancing the carrier and causing the package to strip the stamp from 5 said holding means, and means for pressing the ends of the stamp against the package as the holder and package are advanced upon a further movement of the carrier.

25. In a machine for applying stamps to 10 packages, the combination of an endless carrier having a series of package-holders, each holder comprising a support, a fixed jaw and a spring-pressed movable jaw; a plurality of cams arranged in line with the run 15 of the carrier for opening said movable jaws at a package-receiving position, a package-discharging position and an intermediate stamp-placing position; means for placing a pasted stamp between the package and the 20 then open jaw at the stamp-placing position of the carrier; and means for pressing the ends of the stamp against the package as the carrier is moved forward.

26. In a machine for stamping packages 25 having an indented end, the combination of a package-holder; means for placing a stamp over the indented end of the package; means carried by the package-holder for pressing that portion of the stamp which 30 overlies the indented portion inwardly against such indented portion; means for pressing the ends of the stamp against the package; and rollers acting against the stamp at the corner or edge of the package.

35. 27. In a machine for stamping packages having an indented end, the combination of a package-holder; means for placing a stamp over said indented end; a clamping contact-jaw carried by the package-holder contact- 40 ing with the central portion of the stamp and carrying it into contact with the indented face of the package; means for pressing the ends of the stamp against the sides of the package; and a series of rollers ar- 45 ranged to act on the stamp adjacent the corners of the package.

28. In a machine for stamping packages, the combination of an endless carrier having 50 a series of package holders embodying a fixed and a spring pressed jaw, said jaws being shaped to enter the indented ends of a package held between the same; means for advancing the carrier step by step; a rotatable stamp presenter having a space 55 through which the holders and packages may pass; means for successively placing stamps thereon in adhesive relation; means working in timed relation to the carrier advancing means, for imparting a step by step 60 rotation to the stamp presenter; means for successively opening the clamping jaws aforesaid when the same come into line with the stamp presenter and allowing said jaws to close when a stamp has been positioned 65 and the carrier again moves forward; and

means located along the path of travel of the carrier for causing adherence of the stamp ends to the package.

29. In a machine for applying stamps to packages, the combination of an endless carrier having a series of package-holders, each holder comprising a support, a fixed jaw and a spring-pressed movable jaw; a plurality of cams arranged in line with the run 70 of the carrier for opening said jaws at a package-receiving position, a package-discharging position, and an intermediate stamp-placing position; means for feeding packages successively into the carriers at a package-receiving position; means for placing a pasted stamp between the package and the then open jaw at the stamp-placing position of the carrier; and means for pressing the ends of the stamp against the package 80 as the carrier is moved forwardly.

30. In a stamp-applying machine the combination of stamp pasting means; means for holding the pasted stamp in extended position; package-carrying means; means forming part of said carrying means 90 for pressing a section of the stamp against the package; and means for wiping the remainder of the stamp against the package.

31. In a stamp-applying machine, the combination of means for holding a pasted 95 stamp in extended position; package-carrying means; means forming part of said carrying means for pressing a section of the stamp against the package; means for wiping the remainder of the stamp against the pack- 100 age; and means for creasing the stamp inwardly at the edges of the package.

32. In a stamp-applying machine, the combination of means for holding a pasted stamp in an extended position; package-carrying means including an element adapted 105 to press the stamp intermediate its ends into contact with the package; means for wiping the ends of the stamp against the package; and rollers acting upon the stamp where it 110 is bent over the edges of the package to crease or pinch any projecting portion of the stamp inwardly.

33. In a stamp applying means, the combination of means for receiving and holding 115 a pasted stamp in an extended position; means for applying paste to a stamp and simultaneously placing the same in adhesive relation with said receiving means; means for securing a relative movement between 120 said parts, whereby the stamp may be exposed to a package; and package presenting means, adapted upon a relative movement of the package and stamp receiving means, to strip the stamp from the latter.

In testimony whereof we have signed our names to this specification.

GEORGE WILBUR GWINN.
JAMES W. LEARY.
